UNITED STATES PATENT OFFICE

DONALD S. BARROWS, OF ROCHESTER, NEW YORK, ASSIGNOR, BY MESNE ASSIGNMENTS, TO THE SYMINGTON COMPANY, A CORPORATION OF MARYLAND

DRAFT-KEY COTTER

Application filed November 24, 1924. Serial No. 751,930.

The invention relates to retaining devices for use in connection with removable securing elements and more particularly to an attachment or washer to be employed in connection with a species of cotter.

The primary object of the invention, generally stated, is to provide an attachment or washer device intended to be used in connection with the hairpin cotters provided for 10 the purpose of preventing the displacement of the keys in a draft rigging or gear though as a matter of fact the device is capable of wider application inasmuch as it might be employed in connection with other elements 15 in many different types of apparatus or mechanisms.

A more specific object of the invention is the provision of an attachment or washer device associated with and held in place by the 20 ordinary hairpin cotter, the device being of such construction as to prevent contact of the cotter with the car frame or any portion of the draft gear, thereby avoiding wear and strain upon the cotter while providing greater bearing or wearing surface for the engagement of the relatively stationary portion of the cooperating or coacting elements.

Another object of the invention is to provide a combined washer and cotter adapted 30 to be applied to the key of a draft rigging as a unit, said washer member being so devised as to provide a form for the bight portion of the cotter.

An additional object of the invention is 35 the provision of an attachment or auxiliary device of this character which, being formed preferably as a single piece or casting, will be extremely simple and inexpensive to manufacture and easy to apply in addition to possessing the other above mentioned advantageous characteristics.

To these and other ends the invention may comprise the structural arrangement to be hereinafter set forth, though the specified 45 construction disclosed is merely for purposes of illustration as variations may be made within the scope of the invention.

In the drawings:

Figure 1 is a side elevation of a draft rigging and a portion of the car underframe

with which the draft rigging cooperates, the keys being equipped with my device.

Figure 2 is a plan view of a portion of a draft key embodying the invention.

Figure 3 is a cross section on the line 3—3 of Figure 2.

Although the invention is advantageously applicable to key-connected draft rigging, generally, I have, for purposes of explanation, illustrated as applied to a draft rigging mechanism of the character shown and described in the patent to I. O. Wright, et al., No. 841,757, issued January 22nd, 1907.

Referring to the drawing in detail, the numeral 1 designates a coupler of the draft rigging, 2 and 3 the followers, and 4 the springs located therebetween. These movable parts of the draft rigging are maintained in proper position between the center sills 5 by means of keys 6. The end sill is indicated by the numeral 7 while the striking casting and coupler carry-iron are designated by 8 and 9, respectively.

On account of the constant movement of the transversely extending keys under normal conditions of operation of the draft rigging and the tendency of the keys to move laterally when the cars are rounding curves, it becomes necessary to provide means cooperating with the keys for retaining them in proper assembled relation. Means for accomplishing this purpose must necessarily, to be practicable, present a large wearing area or surface and must also permit side movement of the keys in addition to being readily detachable to enable the keys to be withdrawn when repairs to the draft gear parts are needed. It is a common practice to utilize U-shaped or hairpin cotters 10 which have their arms or side portions engaged through holes 11 in the keys and their ends subsequently upset or clenched.

Under some circumstances it has been found that the friction and shearing strain upon these cotters are such as to wear them away or break them off. This is due to the small area of the cotter which is in contact with the sill or cheek plate and to the fact that the cotter must be made from relatively soft material to permit the necessary bend-

ing and rebending thereof. It has also been found that the corners of the bight portion are sometimes bent too sharply, causing failure at these points. It is with these facts in view that I have designed the present auxiliary device or attachment which may in actual practice be formed as a single piece or casting and which includes a body member 12 having an elongated base portion 13 adapted to contact and preferably conform to the surface of the key to which it is applied. The body 12 further includes an upstanding central portion 14 considerably reduced in length as compared with the base 15 and formed with an opening 15 of such size as to admit the cotter 10 to be threaded therethrough. The opposite end portions of the body are provided with means for engaging the respective arms of the cotter, and said means may comprise forked or slotted openings, as indicated at 16, the inner ends 17 of the forks or slots being rounded off and merging into or formed as continuations of the lower wall or portion 18 of the opening 15. The curved surface formed by the portions 17 and 18 is intended to correspond to the shape of the bight portion of the cotter. The distance between the ends of the inner walls of the forks or slots 16 corresponds substantially to the distance between the holes 11 in the key.

The base member 12 and cotter 10 are assembled prior to the bending of the cotter into the hairpin shape, by inserting the bar from which the cotter is formed through the opening 15. The ends of the member are then bent downwardly so that the bight portion of the cotter coincides with the surface of the casting. It will be observed that the configuration of the surface of the member 12 in a plane parallel with the axis of the opening 15, as shown in Figure 3, is semi-elliptical. This semi-elliptical portion of the washer 12 forms in effect a die member about which the cotter 10 is bent into the hairpin shape. Owing to the contour of the central longitudinal section of the member 12, all danger of forming sharp corners in the cotter is avoided, and after the bar for forming the cotter is bent around said member it cannot be accidentally removed therefrom, as will be obvious. Since the distance from the vertical edges 17 of the casting 12 is substantially equal to the distance between the openings 11 in the draft key 6, the washer and cotter may be readily applied to the draft key without difficulty. After the application the projecting ends of the cotter are bent out of alignment with the axes of the openings 11 so as to prevent the accidental withdrawal of the cotter in service.

It will be noted that both sides and both ends of the device are the same, a feature of importance in facilitating assembling and mounting. When the device is in place the

cotter itself is out of contact with the center sills of the car, the wear being taken by one of the sides of the attachment or washer device. As these sides are comparatively large there is ample wearing surface provided. The curved surfaces 17 and 18 are of importance inasmuch as they will maintain the bight portion of the cotter in normal condition and shape so that under no circumstances will there be any excessive sharpness in the bend which under ordinary conditions frequently results in breakage. Owing to the fact that both sides and ends of the attachments are the same it will be seen that in case of wear the washer device may be turned around so that the unworn side will be presented to the center sills, if such should be found advisable for any reason.

From the foregoing description and a study of the drawings it will be apparent that the device will be of material advantage and will operate most efficiently as retaining means for the draft keys while permitting them to have the movement necessary to their proper action. Danger of breakage from excessive wear and too sharp bending at the corners are entirely avoided and resultant displacement of the key or keys prevented.

I claim:

1. In combination with a draft key provided with a pair of spaced holes and forming part of a draft rigging, an auxiliary member with its bottom surface disposed upon the top of the key between the holes, a cotter embracingly engaging said member and positioned with its arms in the holes, said auxiliary member having its sides extending outwardly beyond the cotter for preventing the engagement of the cotter with any portion of the draft rigging and providing a relatively large bearing area.

2. In combination with a retaining cotter for a draft key forming part of a draft rigging, an auxiliary member disposable upon the key and embracingly engaged by the cotter, said auxiliary member having a surface conformingly engaging the intermediate part of the cotter for maintaining the cotter in normal shape.

3. The combination with a draft key and retaining hairpin cotter therefor, of a washer device disposable upon the key and having openings for the passage of the arms of the cotter, the washer device having an intermediate portion through which the cotter extends.

4. The combination with a draft key and retaining hairpin cotter therefor, of a washer device disposable upon the key and having openings for the passage of the arms of the cotter, the washer device having an intermediate portion through which the cotter extends and further having a curved surface against which the inner portion of the bight of the cotter engages whereby to maintain

the cotter in normal shape and prevent too sharp bending thereof.

5. The combination with a draft key and U-shaped cotter therefor, of a retaining member comprising a body having a base portion disposable upon the key and slotted for the passage of the arms of the cotter, said member having an intermediate portion apertured for the passage of the bight portion 10 of the cotter therethrough, both sides of the body projecting beyond the cotter.

6. The combination with a draft key and U-shaped cotter therefor, of a retaining member comprising a body having a base portion 15 disposable upon the key and slotted for the passage of the arms of the cotter, said member having an intermediate portion apertured for the passage of the bight portion of the cotter therethrough, both sides of the 20 body projecting beyond the cotter, the sides and ends being counterparts whereby the member may be reversible.

7. A device of the character described comprising a body including a base portion 25 and an integral upstanding intermediate portion, the ends of the base portion being slotted for the passage and reception of the arms of a U-shaped cotter, said intermediate portion being apertured for the passage of 30 the cotter, the inner ends of the slots merging into the lower wall of the aperture to define a continuous curved surface forming a bearing for the bight portion of the cotter and acting to maintain the same in normal 35 shape.

8. An auxiliary member for draft keys comprising a base portion adapted for being seated on the end of a key which is normally perforated for the reception of a retaining 40 cotter, said member being provided with slots registering with the perforations in the key and a curved surface extending upwardly and inwardly from the slots, an upstanding portion overlying the corresponding 45 portion of the curved surface and formed with an aperture over and along said surface, a bar for forming a cotter, said surface serving as a forming die for bending the bar to the desired shape for the cotter and being of 50 such a contour that after bending the cotter cannot be accidentally removed therefrom.

9. A washer for use with draft key cotters comprising a base portion adapted for being 55 positioned on the end of a draft key adjacent apertures for the reception of a cotter, said washer being provided with slots registering with said apertures and a surface extending upwardly and inwardly from said slots and 60 being elliptical in contour between said slots, an upstanding eye overlying the intermediate portion of said curved surface providing an aperture for the reception of said cotter, said curved surface serving as a forming die 65 around which the cotter is bent and from

which it cannot be accidentally removed after bending to the desired shape.

10. In combination with a retaining cotter for a draft key forming part of a draft rigging, an auxiliary member disposed lengthwise on top of said key and of a length less than the width thereof, the end of said member having notches and embracingly received between intermediate portions of the cotter with the arms thereof fitting in said notches. 70 75

In testimony whereof I affix my signature.
DONALD S. BARROWS.
